Franklin D. Long

UNITED STATES PATENT OFFICE.

WILLIAM A. LEE, OF PEORIA, ILLINOIS.

MECHANISM FOR OPERATING STREET-CAR SWITCHES.

SPECIFICATION forming part of Letters Patent No. 439,354, dated October 28, 1890.

Application filed May 27, 1890. Serial No. 353,389. (No model.)

To all whom it may concern:

Be it known that I, WILLIAM A. LEE, a citizen of the United States, residing at Peoria, in the county of Peoria and State of Illinois, 5 have invented certain new and useful Improvements in Mechanism for Operating Street-Car Switches; and I do declare the following to be a full, clear, and exact description of the invention, such as will enable 10 others skilled in the art to which it appertains to make and use the same, reference being had to the accompanying drawings, and to the letters of reference marked thereon, which form a part of this specification:

15 This invention relates to certain new and useful improvements in means for operating street-car switches; and it has for its object to generally improve upon the construction and render more efficient in operation that 20 class of street-car switch-operating mechanism which is adapted to be operated by the drivers of horse-cars or gripmen or other operators of either cable or electric cars, and which will serve to properly adjust the switch 25 without necessitating the stoppage of the car.

The invention has for a further object to so arrange the operative parts of the switch-operating mechanism that they can by no possibility become inoperative by reason of the 30 accumulation of dust or dirt.

The device is simple and inexpensive in construction and will not be liable to get out of order. Provision for permitting ready access to the parts is provided, and the parts 35 which would be liable to be affected either by wear or by changes in temperature are made adjustable.

To the above ends and to such others as the invention may pertain the same consists in 40 the peculiar construction and in the novel combination, arrangement, and adaptation of parts, all as more fully hereinafter described, shown in the accompanying drawings, and then specifically defined in the appended 45 claim.

The invention is clearly illustrated in the accompanying drawings, which, with the letters of reference marked thereon, form a part of this specification, like letters of reference 50 indicating like parts throughout the several views, and in which drawings—

Figure 1 is a top plan view of a portion of

a street-car track provided with my improved operating mechanism. Fig. 2 is a cross-section through the switch upon the line *xx* of 55 Fig. 1, showing also the end of a car with the switch-operating rods. Fig. 3 is a perspective detail view of the frog and its connections.

Reference now being had to the details of 60 the drawings by letter, A A represent the rails of the main track, and B B the rails of the siding or switch.

C is a casting, which is bolted or otherwise 65 securely attached to the bed-timbers B' and B², which timbers are secured to the road-bed midway between the tracks of the main line in such a position that the space B³ between the timbers is directly opposite the movable end of the pivoted frog C'.

Secured to the upper end of the vertical shaft D, which passes through a suitable opening in the casting C at a point midway between the timbers B' and B², is the angle-lever D', which lever is adapted, when turned, as hereinafter described, to move upon the upper face of the casting C, suitable wearing-blocks a a being provided upon the under side of the lever at the ends of the arms D' and D². The lower end of the shaft D is supported in the plate E, said plate being adjustably attached to the upper face of the plate E', said plate being secured at its ends to the lower faces of the timbers B' and B². The body of the shaft D between the plate E and the casting C is enlarged, and is preferably 85 square in cross-section. The plate E' is formed with an open-ended slot E² to allow of the insertion of the lower end of the shaft D, and the plate E is adjustably or pivotally connected to the plate E' by the bolt or pivot E², so that said plate E may be adjusted or moved on said bolt or pivot to admit of the insertion of the lower end of the shaft D, and then tightened to retain it in its adjusted position. 90

F is a rod which is attached at one of its ends to the end of the horizontal arm F', which projects from one side of the body portion of the shaft D, the other end of the rod being attached to the lower face of the pivoted frog C' near its free end, as shown, the plates F² and F³ serving both as guides for the rod and also serving to strengthen the parts.

The point C' is pivoted in the usual man-

ner, and is adapted to guide the flange of the passing car-wheel, so as to cause the wheel to follow either the main track or the siding, according to the position that the free end of the point chances to occupy at the time. The outer face of the plate F^3 is recessed, as shown at F^4 , to receive the point when the same is thrown inwardly, so as to cause the passing car to leave the main line and enter the siding.

10 The said block also serves to limit the throw of the point, as will be readily understood.

The upper face of the casting C, adjacent to the angle-lever D', is the substantially triangular raised portion C^4 , which, with the raised ribs C^5 at the outer edges of the casting, serves to guide the switch-operating rods connected to the car-platform, which will be presently described.

15 The bed-piece G of the point C' is provided with a series of openings b b, through which openings the dust, dirt, or other substances which would otherwise tend to clog the path of the point and interfere with the free movement of the same pass a suitable receptacle, as the box H, being provided to catch the same. Said box H is provided with a suitable cover H' upon the outside of the track, which serves as a means for permitting the removal of the contents of the box when desired.

20 I have what I term the "pedal-rods." They are passed vertically through the platform J and are provided at their upper ends with the foot-pieces J⁸. The spiral springs J² upon the rods I serve to hold the rods normally in such 25 position that the foot-rests J⁸ will be about eight inches above the platform and the lower ends of the rods will be substantially the same distance above the level of the road-bed.

25 It will be observed that the pedal-rods are so placed that, depressed in passing over the casting C between the tracks, the said rods will enter the space between the raised portion C^4 and raised portion or rib C^5 upon the upper face of the casting, one of the said rods 40 being adapted to pass upon one side of the portion C^4 and the other upon the opposite side.

30 The operation of the device is simple, and from the foregoing description will be readily understood. We will, for example, suppose that the movable point C' is set in such a position as to cause the car to leave the main line 45 and pass upon the switch or siding; but it is

desired that the approaching car shall continue upon the main track, thus rendering it necessary that the position of the frog should be changed. The driver or gripman upon the front platform of the car places his foot upon the foot-rest at the upper end of the pedal-rod upon the right-hand side, depressing the said rod, and the lower end of the rod entering the space upon the right-hand side of the portion C^4 , will be guided to the right-hand arm of the angle-lever D', throwing said lever to the left and moving the point through the means of the connections between the angle-lever and point, as will be readily understood. It will also be seen that by depressing the opposite pedal-rod the point will be caused to turn in the opposite direction and will be set for the main track.

35 In order to prevent either mud or snow and ice from interfering with the free movement of the pedal-rods, I have provided a casting K, directly beneath the front edge of the car-platform, through which the said rods are passed. It will be readily seen that this boxing will serve to effectually prevent the accumulation of mud or ice upon the body of the rods.

40 Having thus described my invention, what I claim to be new, and desire to secure by Letters Patent, is—

45 The combination, with the casting C between the main tracks and formed upon its upper face with triangular raised portion C^4 and triangular ribs C^5 , of the angle-lever D', pivoted to the casting opposite the portion C^4 and provided with wearing-plates a, the side tracks, the pivoted frog C', the vertical shaft 50 D, passed through an opening in said casting and connected at its upper end to the lever D', the plate E', formed with open-ended slot E³, the plate E, adjustably held to the plate E', the arm F', projecting from the shaft D, the 55 rod F, connecting said arm with the frog, and the guide-plates F^2 and F^3 , the latter recessed in its outer face, substantially as and for the purpose specified.

60 In testimony whereof I affix my signature in presence of two witnesses.

WILLIAM A. LEE.
